UNITED STATES PATENT OFFICE.

RICHARD LESTER WILCOX, OF WATERBURY, CONNECTICUT, ASSIGNEE TO THE WATERBURY FARREL FOUNDRY AND MACHINE COMPANY, OF WATERBURY, CONNECTICUT, A CORPORATION OF CONNECTICUT,

FEED MECHANISM.

1,135,239.

Specification of Letters Patent.

Patented Apr. 13, 1915.

Application filed April 6, 1914. Serial No. 829,749.

To all whom it may concern:

Be it known that I, RICHARD LESTER WILCOX, a citizen of the United States, residing at Waterbury, in the county of New Haven 5 and State of Connecticut, have invented certain new and useful Improvements in Feed Mechanisms, of which the following is a specification, reference being had therein to the accompanying drawings.

10 My invention relates to a new and improved feed mechanism, having particular reference to that type of feed devices associated with heading machines and used for the purpose of intermittently feeding a wire 15 rod to the upsetting dies. While it is particularly adapted for this purpose, and is illustrated herein as connected with a heading mechanism, its availability is not limited thereto, because it may be used with various 20 types of machines requiring a feed device.

It is the object of this invention, among other things, to provide a feed mechanism wherein both of the rolls are capable of adjustment in relation to the line of wire feed 25 irrespective of their diameter, especially with feed mechanism wherein the axes of the feeding rolls are horizontal.

To these, and other ends, my invention consists in the feed mechanism, having certain details of construction and combinations of parts, as will be hereinafter described and more particularly pointed out in the claims.

Referring to the drawings, in which like 35 numerals of reference designate like parts in the several figures; Figure 1 is a side elevation of my improved mechanism; Fig. 2 is a plan view thereof; Fig. 3 is a front elevation, partly in section; and Fig. 4 is a 40 sectional view of the parts, taken upon line A—B of Fig. 3.

In the drawings, the numeral 1 designates the bed of a header, or a part of any other type of machine with which my improved feed mechanism may be attached, in 45 which the line of wire feed, which is always in substantially the same position in relation to the said header, etc., is illustrated by the broken lines C—C.

50 The feed mechanism itself comprises a bracket 2, within which is mounted the shaft 3, having a feed roll 4 at one end and a gear 5 adjacent to the other end, upon which is a friction brake 6. Pivotally secured within

said bracket, upon the stud 7, is the roll 55 frame 8, having the shaft 9 rotatably mounted therein, to one end of which is fixed a feed roll 10 corresponding in shape and size with the feed roll 4, and having a gear 11 secured to the opposite end thereof, the 60 teeth of which mesh into those of the gear 5. The bracket 2 is secured in place to the bed 1 by the bolts 12, 13 and 14, which pass through elongated slots 15 in said bracket and are threaded into the bed 1. 65

Fixed to the bed 1 is a guide strip 16, which projects into a slot in the rear of the bracket 2 so as to insure the positive vertical movement of said bracket in relation to said bed, said strip being formed with a lug 17 at its bottom end, through which is threaded a screw 18, having a lock nut 19 thereon, which screw abuts against a button 20 fixed in the bottom of said bracket. The wire is guided between the rolls 4 and 10 70 by a quill 21, having an opening therethrough, the axis of which is coincident with the feed line C—C of the machine. This quill is secured to the bracket 2 by a plate 22 that is fixed thereto by the bolts 75 13 and 14, which pass therethrough, a screw 23 in said plate holding the quill against movement therein. As the rolls 4 and 10 wear they can be resized and reshaped and used over again, the difference in diameters 80 occasioned by such resizing being accommodated by moving the bracket 2 upwardly through the screw 18 until the periphery of the lower roll is again brought to the feed line C—C, while the roll 10 is always held 85 in contact with the lower roll by the action of the spring 24, which rests on the top of the roll frame 8, its tension being varied by a screw 25 in the yoke 26, which bears 90 against the washer 27 resting on the top of said spring. A rod 28 projecting through the head of the screw 25 provides ready means for rotating said screw, and a lock nut 29, having an arm 30, holds the screw 95 against premature rotation. 100

It has heretofore been possible to grind only one of the rolls, the upper roll, because if the diameter of the lower roll is reduced, the periphery thereof will not touch the line of the wire feed, its proper 105 position for a successful feed operation. With my improved mechanism, however, both rolls may be resized an endless num-

ber of times, and the lower roll will always be in the line of the wire feed by a proper relative adjustment of the bracket upon the bed.

5 Intermittent rotary movement is imparted to the roll shafts 3 and 9 through the link 31, having an endwise movement, and a pawl carrier 32 rotatably mounted upon the shaft 3, carrying a pawl 33 that engages the teeth of the ratchet disk 34.

The above described mechanism for imparting rotary movement to the feed rolls constitutes no part of this invention.

Within the scope of the appended claims, 15 the details of this invention may be materially varied, and I therefore desire to have it understood that I do not limit myself to the exact construction herein shown and described.

20 Having described my invention, what I claim as new and desire to secure by Letters Patent, is:

1. In a feed mechanism, the combination with a machine body having a substantially 25 fixed line of wire feed; of a bracket; means for adjustably securing said bracket to said

machine body; a shaft journaled in said bracket; a roll frame pivotally connected with said bracket; a shaft journaled in said roll frame; a feed roll for each of said shafts; and means for applying an adjustable, yielding pressure to the free end of said roll frame.

2. In a feed mechanism, the combination with a machine body having a substantially fixed line of wire feed; of a bracket connected with said machine body; companion feed rolls, one above the other, rotatably connected with said bracket; means for adjusting the relative position of said bracket 40 whereby the lower of said rolls is moved toward and away from said line of wire feed; and means connected with said bracket for maintaining the upper of said rolls in contact with the lower roll in any 45 of its adjusted positions.

In testimony whereof I affix my signature in presence of two witnesses.

RICHARD LESTER WILCOX.
